UNITED STATES PATENT OFFICE.

GEORGE H. MACDONOUGH, OF BOSTON, MASSACHUSETTS.

FOUNTAIN-PEN.

1,357,068.

Specification of Letters Patent.

Patented Oct. 26, 1920.

Application filed April 10, 1919. Serial No. 288,998.

To all whom it may concern:

Be it known that I, GEORGE H. MACDONOUGH, a citizen of the United States, and a resident of Boston, in the county of Suffolk and State of Massachusetts, have invented an Improvement in Fountain-Pens, of which the following description, in connection with the accompanying drawings, is a specification, like characters on the drawings representing like parts.

This invention relates to fountain pens of the so-called self-filling type wherein mechanism is associated with the pen by means of which the supply of ink may be renewed, and the object is to provide an improved construction not likely to get out of order and of superior convenience and durability.

My invention will be best understood by reference to the following description of a specific embodiment of my invention disclosed by way of illustration in the accompanying drawings wherein:

Figure 1 is a part elevation and a part longitudinal section through a pen;

Fig. 2 is a partial section on an enlarged scale with the parts in another position;

Fig. 3 is a plan of the presser bar and attendant mechanism; and

Figs. 4 and 5 are sections on the lines 4—4 and 5—5 respectively, of Fig. 1.

Referring to the drawings, I there show a fountain pen of the type wherein the usual barrel or body 7 of the pen contains an ink reservoir in the form of a collapsible sack 9 of rubber or similar material, which sack may be compressed by means of a suitable presser bar 11. Such a structure is well known and does not require further description.

The presser bar 11 is herein operated by a lever 13 pivoted at 15 to the barrel of the pen and having a cranked end portion 17 extending over the bottom or base of the barrel and terminating in a finger grip 19 substantially aligned therewith. The lever 13 works in the longitudinal slot 21 of the barrel, best shown in Fig. 2, which slot terminates short of the end of the barrel which is thus provided with an unbroken basal closure 23. The walls of the slot are thus held in definitely spaced relation at each end thereof, providing a working space for the lever which will freely and yet snugly receive the same and the shape of which is not likely to be changed in use in such a way

as to either bind on the lever or permit too free motion thereof.

As shown in Fig. 4, the pivot 15 for the lever extends between the walls of the slot and may serve as a spacing means therefor 60 between its ends. In its closed position the lever may lie substantially flush with the exterior of the barrel, as shown in Fig. 1. To permit the provision of a finger grip 19 exterior to the barrel, the end of the barrel 65 adjacent its base is provided with a groove 25, best shown in Fig. 2, opening into the slot 21, which groove, however, preferably does not extend through the full thickness of the barrel wall but leaves a part thereof 70 intervening as a brace to hold the sides of the slot apart, thus effectually preventing them from being jammed together, as for example by the pressure of the cap 26 when it is placed over the base of the barrel. If the 75 barrel were so bent adjacent the slot under certain conditions of temperature under which the material of the barrel would be to a degree plastic, the barrel might take a permanent set with the walls of the slot gripping 80 tight on the sides of the lever 13.

Conveniently the lever 13 is constructed of suitable sheet material of a thickness corresponding to the depth of the slot 25. At the left hand end of the lever, viewing the 85 figures, it is provided with flanges 27 providing an operating portion for engagement with the presser bar 11, as shown in Fig. 4, and lending stiffness to the lever as a whole. The right hand portion is bent inwardly or 90 cranked at 17 over the base of the barrel, and conveniently this bent end portion may be extended somewhat obliquely to avoid the weakening effect of too sharp a bend and the material of which the lever is formed may 95 be flanged also on the right hand end to strengthen the same, the flanges conveniently increasing in depth and being rolled or bent to provide a substantial finger grip 19.

To accommodate the portion 17 of the 100 lever, the base 23 of the barrel may be made of substantial thickness and is conveniently provided with an enlargement or boss 29 for a purpose to be described. As best seen in Fig. 2, the base of the boss 29 may be radially grooved, the groove 31 communicating with the groove 25 in the side of the barrel, sloping toward the groove 25 to accommodate the obtusely bent lever and merging into the same along a rounded surface 33. 110

The bent end 17 of the lever 13 seats in the slot 31 when the lever is in closed position and finds substantial support in the end closure of the barrel.

- 5 5 To cover and protect the finger grip 19, I may provide a removable cap 35 of the same exterior dimensions as the barrel, which may be threaded onto the boss 29 in the manner indicated in Fig. 1.
- 10 10 To support the presser bar 11 within the barrel and to aid in returning it to the position shown in Fig. 1, after the sack 9 has been deflated, it may be supported by a suitable spring. Herein the spring com-
- 15 15 prises a split ring 37 (see Fig. 5) which may be housed at the base of the barrel and by its resiliency grips the interior thereof. Integral with this spring is the tongue 39 which in the present embodiment of the in-
- 20 20 vention is inwardly bent across the ring and then backwardly toward the open end of the barrel, as shown in Fig. 1. The tongue 39 overlies the presser bar 11 and may be permanently secured thereto in any desired
- 25 25 manner, herein by means of integral lugs 41 (Figs. 3 and 4) formed on the presser bar 11 and bent over the sides of the spring tongue 39. To permit the lever 13 to engage the presser bar 11 and further to provide
- 30 30 a guide for the lever and also to aid in positioning the presser bar and spring properly in the barrel, the spring arm 39 is provided with a slot 43 (Fig. 3). The end of the lever extends through this slot to make
- 35 35 contact with the presser bar 11, the lever being guided by the sides of the slot. In the present embodiment of the invention the slot is an open-ended slot. In other words, the spring tongue 39 is bifurcated,
- 40 40 providing a pair of tines which are engaged and held to the presser bar 11 by the ears 41.

Having thus described the particular embodiment of my invention herein shown by way of illustration, what I claim as new and desire to secure by Letters Patent I shall express in the following claims:—

- 45 1. In a self filling fountain pen of the type described, a barrel having a closed end, a slot in the side and a groove extending from the slot to the closed end of the barrel, and an operating lever working in said slot having a portion received in said groove and a portion alined with the barrel.
- 50 55 2. In a self filling fountain pen of the

type described, a barrel having a closed end of substantial thickness, a slot in the side of the barrel terminating above said end, said end having a radial groove with a sloping bottom, and a lever working in the slot having an obtusely bent portion received by the groove and a terminal portion exteriorly presented at the base of the barrel.

3. A structure as described in claim 2, 65 wherein the side of the barrel has a groove extending between the end of the slot and the radial groove into which the lever fits.

4. In a self filling fountain pen of the type described, a barrel having a closed end 70 provided with a boss and having a slot in the side terminating above said end, said boss having a substantially radial groove sloping toward the slot, a lever working in the slot having an obtusely bent portion 75 received by the groove and a terminal portion alining with the barrel, and a cap fitting said boss to inclose said terminal portion.

5. In a self filling fountain pen of the 80 class described, a barrel having a closed end, having a slot in the side terminating short of said end, and also having a groove extending from the slot to said end, and a cranked operating lever comprising a plate 85 fitting substantially flush in said groove, having a flanged portion pivoted in the slot and a flanged portion providing a finger grip at the base of the barrel.

6. In a self filling fountain pen of the 90 type described, a barrel having an unbroken basal closure and a longitudinal slot along one side of the same terminating short of the base, and a lever pivoted in the slot and having a cranked portion extending inwardly over the base. 95

7. In a self filling fountain pen of the type described, a barrel having an unbroken basal closure and a longitudinal slot along one side of the same terminating short of 100 the base, and a lever having a substantially flat portion, a flanged portion at one side thereof pivoted in the slot and a cranked portion extending inwardly over the base of the barrel and flanged to provide a finger 105 grip.

In testimony whereof I have signed my name to this specification.

GEORGE H. MACDONOUGH.
